UNITED STATES PATENT OFFICE.

WILLIAM H. MILES, JR., OF BROOKLYN, NEW YORK.

DESIGN FOR A WALL-POCKET.

SPECIFICATION forming part of Design No. 14,768, dated February 19, 1884.

Application filed December 20, 1883. Term of patent 34 years.

To all whom it may concern:

Be it known that I, WILLIAM H. MILES, Jr., of Brooklyn, county of Kings, and State of New York, have invented a new and useful 5 Design for Wall-Pockets and Packing-Cases, of which the following is a full, clear, and exact description, reference being had to the accompanying drawings, and to the letters of reference marked thereon.

10 Figure 1 is a front elevation of my newly-designed wall-pocket and packing-case, and Fig. 2 a side elevation of the same.

In both figures like letters refer to corresponding parts.

15 Heretofore these pockets or cases have generally been made square or rectangular in front elevation, and having the front variously ornamented by painting and otherwise.

The leading feature of my design is the cylindrical form given the frame, which projects 20 well back from the front or mirror, and made to represent the general form of a tambourine.

A is a back plate, shown larger than the frame, and in rectangular form.

25 B is the front plate, which is a mirror, the same having the beveled edge all around, and made in circular form.

C is the wall of the frame, extending well 30 back from the front piece, which is located in the front of the frame, giving the frame the appearance of considerable depth, but little width outside the margin of the front piece.

D are circular plates arranged in the wall

of the frame, like the cymbal plates (or bells) in an ordinary tambourine, the whole being 35 arranged to represent the general figure of a tambourine, as shown in the drawings. The frame C is ornamented in any desired manner. The back A is ornamented so as to harmonize with the frame, all presenting a pleasing and 40 attractive appearance.

The dotted line E represents a brush-handle projecting from the frame.

Having now fully described my design, what I claim as new, and desire to secure by Letters 45 Patent, is—

1. The herein-described design for a wall-pocket and packing-case, consisting of the circular front piece having the beveled edge, and the circular frame provided with the circular plates, substantially as shown and described. 50

2. The herein-described design for a wall-pocket and packing-case, consisting of the circular front piece, the cylindrical frame surrounding the same, and the circular plates located in the walls of the cylinder, and the rectangular back piece, substantially as set forth. 55

In testimony that I claim the foregoing I have hereunto set my hand in the presence of two witnesses.

W. H. MILES, JR.
